ALONZO T. BOON, OF GALESBURG, ILLINOIS.

Letters Patent No. 63,004, dated March 19, 1867; antedated March 1, 1867.

IMPROVEMENT IN GAS HEATERS AND PETROLEUM STOVES.

The Schedule referred to in these Letters Patent and making part of the same.

TO ALL WHOM IT MAY CONCERN:

Be it known that I, ALONZO T. BOON, of the city of Galesburg, in the county of Knox, and State of Illinois, have invented a new and useful Improvement in Vapor Stoves for Burning Petroleum; and I do hereby declare that the following is a full, clear, and exact description of the construction and operation of the same, reference being had to the accompanying drawings, making a part of this specification, in which—

Figure 1 is a top view of my improved vapor stove.

Figure 2, a vertical section of the same, as indicated by the line $x y$ in fig. 1.

Like letters in both figures of the drawings indicate like parts.

My invention has reference to vapor stoves for burning coal oil, naphtha, or benzine, (or the ordinary gas may be used,) and is designed for use in warm weather, or where it is not desired to heat the room.

I have a cylindrical stove, A, supported on suitable legs, and having a portion of the bottom, of a funnel shape, a , constructed up inwardly therefrom. Within the stove, and bolted properly to the funnel-shaped bottom thereof, is a heat-conductor, B, of a cylindrical ogee form, and made sufficiently smaller than the outer cylinder as to have an air-chamber, b , intervene between the two. The outer cylinder is provided with a suitable number of perforations, c , for the admission of cold air to the chamber. Elevated and supported by a tube, C', is a reservoir, D, in which hydrocarbon liquids are placed. The tube C' is connected with a horizontal one, C, by an air and gas-tight joint, d , at which point is a temper-screw, e , for regulating the flow of the liquid into the horizontal tube. The horizontal tube projects downward at right angles, and is curved through the side of the funnel-shaped bottom, the end terminating at the mouth of the funnel. A cap or burner, f , is screwed on to the end, having a small hole through the centre of it to permit the gas that may be generated to escape.

The horizontal tube is made to pass through a solid heater or generator, E, or it may be made to pass over the same and then secured to it. The heater is of a circular shape, and provided with a cone, g , over the burner, and having a concave surface formed from the sloping sides of the cone to the periphery of the heater.

As the liquids would perhaps flow too rapidly in the tubes from the reservoir to the heater, and thus endanger the person volatilizing the liquid, a bundle of short, fine wire, held together by bands, is introduced in the tube near the heater, the effect of which will be to retard the flow of the liquid sufficiently just before reaching the heater to prevent this. This bundle of wire is represented by F, and is not shown in the tube as above described, not deeming it necessary, as it will be obvious its connection therewith will be readily understood.

The point of my invention is this: The effect of the funnel-shaped bottom of the stove will be to concentrate a strong current of air at a given point (its mouth) around the burner, that is, when the liquid has become sufficiently volatilized by the action of heat independently applied to the heater, other than that produced from the liquid, which volatile or gaseous matter mixing with the current of air thus obtained will create a steady and powerful flame, and consequently a powerful heat upon the heater, and which, if the under surface of the heater was entirely a plain one, the heat would probably affect the tube over or in it to such an extent as to cause an explosion of the fluid therein; therefore to obviate this it will be found that the point of the cone will deflect the flame radially therefrom, and by the concave surface of the heater it will be caused to expand itself somewhat obliquely downwards from the edge of the heater on to and within the concave part of the ogee cylinder. It will now be observed from the swelling in or contraction of the upper part of the cylinder to a convex form, the heat ascending will become concentrated at this point, and hence will be expanded fully from the diverging sides of the cylinder upon the cooking utensil that may be placed above on the stove.

Operation: The reservoir is filled with naphtha or benzine; a sponge, affixed to a piece of wire, saturated in alcohol and set on fire, is then applied to the mouth of the funnel, so that the heat will reach the heater. After holding it a moment, or until the heater becomes sufficiently hot, the temper-screw is turned slightly, so as to allow the fluid to flow, and when it reaches the wire it will permeate slowly through it and thus gradually come in contact with the heating surface of the tube, at which point its reduction to a gaseous state will be indicated by its ignition at the burner from the contact of the flame of the sponge therewith. The sponge is then withdrawn, and the burner continues to supply itself automatically.

By detaching the horizontal tube, or that part of it extending to the mouth of the funnel, and applying the ordinary gas from a burner stand having a gutta-percha tube attached thereto and connecting with a ceiling or

wall burner, the heater may be heated, and the cone so affect the flame as to cause a communication of the heat therefrom to the ogee cylinder in the manner herein described.

It will be found that the perforations will admit the necessary amount of cold air to the chamber to prevent the outer cylinder from becoming too hot, so that no discomfort will be occasioned in the use of the stove in warm weather.

Having thus fully described my invention, what I claim therein as new, and desire to secure by Letters Patent, is—

The bundle of short, fine wire F, in combination with the horizontal tube C, substantially in the manner and for the purpose as herein set forth.

The solid heater E, as constructed, and provided with a cone, g, in combination with the horizontal tube C, substantially in the manner and for the purpose as herein set forth.

The ogee cylinder B, in combination with the funnel-shaped bottom a of the stove, substantially in the manner and for the purpose as herein set forth.

ALONZO T. BOON.
